UNITED STATES PATENT OFFICE.

LEONIDAS D. WEST, OF DUNDEE, NEW YORK.

APPARATUS FOR PRODUCING COMBUSTION.

SPECIFICATION forming part of Letters Patent No. 665,947, dated January 15, 1901.

Application filed May 7, 1900. Serial No. 15,689. (No model.)

To all whom it may concern:

Be it known that I, LEONIDAS D. WEST, of Dundee, in the county of Yates, in the State of New York, have invented new and useful 5 Improvements in Apparatus for Producing Combustion, of which the following, taken in connection with the accompanying drawings, is a full, clear, and exact description.

My invention relates to apparatus for producing combustion, the object being to increase the efficiency of the heater and at the same time to decrease the cost of maintaining a uniform and high degree of heat within the combustion-chamber.

15 To this end the invention consists in the construction and arrangement of the component parts of an apparatus for the purpose mentioned, as hereinafter fully described, and pointed out in the claims.

20 In describing this invention reference is had to the accompanying drawings, forming a part of this specification, in which like figures indicate corresponding parts in all the views.

Figure 1 is a perspective view, partly broken 25 away, of a heater embodying my invention. Figs. 2 and 3 are enlarged sectional views taken, respectively, on lines 2 2 and 3 3, Fig. 1. Fig. 4 is a sectional view taken on line 4 4, Fig. 3.

30 1 represents a heater, as a stove, which is of any desired form or size and is provided with a combustion-chamber, a smoke-conduit 3, and an inlet-opening 4, arranged beneath a suitable grate 5 at the base of the combustion-chamber 2.

The smoke-conduit 3 may be connected to the combustion-chamber 2 in any desired manner, and is provided with a damper 6 for controlling the passage of the escaping products of combustion therethrough and with an opening 7 extending through one of its side walls between the damper 6 and the combustion-chamber 2.

Arranged within the smoke-conduit 3 is an 45 air-conduit 8, having one end registered with the opening 7 and communicating with an air-inlet chamber 9, said inlet-chamber being secured to the outer face of the smoke-conduit 3 and provided with one or more apertures 10, communicating with the atmosphere or other supporter of combustion. The op-

posite end of the air-conduit 8 extends within the combustion-chamber 2 and is connected to an air-drum 11, extending into the combustion-chamber and having apertures 12, 55 also communicating with the atmosphere.

Suitable closures 13 and 14 are movable into and out of registration with the apertures 10 and 12 for regulating the quantity of air admitted to the conduit 8. It is thus apparent 60 that the opposite ends of conduit 8 communicate with the atmosphere when desired and that the air may be admitted through the apertures of one end of the conduit 8 independently of the other by closing one of the 65 closures and opening the other closure.

15 represents a branch conduit arranged within the combustion-chamber and having one end connected to the intermediate portion of the conduit 8, between the inlet-apertures 10 and 12. The opposite end of the branch 70 conduit 15 extends laterally in a substantial curved horizontal plane and is provided with a downward-deflected extension 16, having lateral openings 17, arranged in close proximity to the surface of the fuel within the combustion-chamber 2.

A suitable damper 18 is arranged within the conduit 8 between the drum 11 and the adjacent end of the branch conduit 15 and serves 80 to close the lower end of the conduit 8 when air is admitted to the opposite end of said conduit.

19 is an air-duct forming a portion of one of the walls of the combustion-chamber and 85 having one end connected to the drum 11 and its opposite end communicating with the atmosphere, preferably at a point beneath the inlet-opening 4 of the heater 1. The duct 19 is provided with a damper 20 for controlling 90 the passage of air therethrough and may be used in connection with or independently of the closures 13 and 14 for controlling the supply of air to the conduit 8.

The operation of my invention is similar to 95 that set forth in my pending process application, Serial No. 13,424, which is based upon the discovery that an inequality of pressure may be maintained within the combustion-chamber and that said unequal pressure is 100 utilized to cause a continuous flow of fresh air to the combustion-chamber, which is heated in

transit thereto for producing a maximum degree of heat with the least possible amount of fuel.

In the operation of my invention when the fuel is ignited the inlet-opening 4 is closed and the escaping products produce an inequality of pressure in the combustion-chamber. One of the closures, as the closure 13, is then opened and a quantity of air proportionate to the inequality of pressure is drawn into the conduit 8 and branch 15 through the opening 17 and into the combustion-chamber 2. During this operation the closure 14 and the dampers 18 and 20 are preferably closed. 15 When desiring to draw the air from the room for ventilation purposes and at the same time supply air to the combustion-chamber, the closure 13 and damper 20 are closed and the closure 14 and the damper 18 are open, there- 20 by communicating the branch conduit 15 with the atmosphere, or, if desired, the closures 13 and 14 may be closed and the dampers 18 and 20 opened, whereupon the air will be drawn from the lower end of the duct 19 into the branch conduit 15 and thence to the combustion-chamber. 25

The operation of my invention will be apparent from the foregoing description and the accompanying drawings, and it will be 30 noted that considerable change may be made in the construction and arrangement of the parts of my invention without departing from the spirit thereof and I do not limit myself to the construction shown and described.

35 Having thus fully described my invention, what I claim as new, and desire to secure by Letters Patent, is—

1. An apparatus for producing combustion comprising a combustion - chamber and a 40 smoke-conduit having an opening in one of its side walls, an air-drum extending into the combustion-chamber, and having an opening communicating with the atmosphere, an air-conduit extending from said opening to and 45 communicating with the air-drum, closures for said openings for the purpose described, and an additional conduit arranged within the combustion-chamber and having one end connected to said air-conduit between the air- 50 drum and the opening in the smoke-conduit and its other end discharging into the combustion-chamber.

2. An apparatus for producing combustion comprising a combustion - chamber and a smoke-conduit having an air-inlet opening 55 extending through one of its side walls, a damper arranged above said opening, a drum having one end projecting into the combustion-chamber and its other end provided with an opening communicating with the atmosphere, closures for said openings in the drum and smoke-conduit, an air-conduit connecting said drum with the opening in the smoke-conduit, and an additional conduit connected to the air-conduit between the drum and the 60 opening in the smoke-conduit and discharging into the combustion-chamber. 65

3. An apparatus for producing combustion comprising a combustion - chamber and a smoke-conduit having an opening in one of 70 its side walls, an air-drum having an opening communicating with the atmosphere, an air-conduit connecting said drum with the opening in the smoke-conduit, an additional conduit connected to the air-conduit between 75 the drum and the opening of the smoke-conduit and discharging into the combustion-chamber, and a damper in the air-conduit between the drum and said additional conduit.

4. An apparatus for producing combustion 80 comprising a combustion - chamber and a smoke-conduit having an opening in one of its side walls, an air-drum provided with an opening communicating with the atmosphere, closures for said openings in the drum and smoke-conduit, an air-conduit connected to the drum and provided with an opening beneath the combustion-chamber, a damper in 85 said air-conduit between the drum and opening, a second air-conduit connecting the drum 90 with the opening in the smoke-conduit, an additional conduit arranged within the combustion-chamber and having one end connected to the second air-conduit and its other end discharging into the combustion-chamber, and a damper in the second air-conduit 95 between the drum and the additional conduit.

It witness whereof I have hereunto set my hand this 26th day of April, 1900.

LEONIDAS D. WEST.
